Primary Examiner — Sandra Snapp*Assistant Examiner* — I. N P(74) *Attorney, Agent, or Firm* — Brick Gentry PC; Brian J. Laurenzo; Jessica L. Susie(57) **CLAIM**

The ornamental design for a grip for a swivel hose coupling as shown and described.

DESCRIPTION

FIG. 1 is a perspective view of a grip for a swivel hose coupling.

FIG. 2 is a left side view of the grip for a swivel hose coupling of FIG. 1.

FIG. 3 is a right side view of the grip for a swivel hose coupling of FIG. 1.

FIG. 4 is a front side view of the grip for a swivel hose coupling of FIG. 1.

FIG. 5 is a rear side view of the grip for a swivel hose coupling of FIG. 1.

FIG. 6 is a top view of the grip for a swivel hose coupling of FIG. 1.

FIG. 7 is a bottom view of the grip for a swivel hose coupling of FIG. 1.

The broken lines in the drawings illustrate portions of the Grip for a Swivel Hose Coupling and form no part of the claimed design.
